MONOALKYL ETHERS OF HEXESTROL AND
METHOD OF PRODUCING SAMEFranz C. Schmelkes, Montclair, N. J., assignor to
Wallace & Tiernan Products, Inc., Belleville,
N. J., a corporation of New JerseyNo Drawing. Application September 26, 1941,
Serial No. 412,425

2 Claims. (Cl. 260—613)

This invention relates to novel synthetic estrogenic products which are derivatives of hexestrol and to an improved method of making same. More particularly, the present application is directed to the discovery of the estrogenic potency of the mono-substituted ethers of 3,4 di-parahydroxyphenyl hexane, which is known in the literature under the short name of hexestrol.

In application Serial No. 375,446, filed January 22, 1941, for medicinal composition and method of making same, there is disclosed a novel process for preparing monoalkyl ethers of phenols of the type of monomethylstilboestrol, which compounds were originally disclosed and claimed in the co-pending application of E. E. Reid, Ser. No. 342,267, filed June 25, 1940, for Medicinal composition.

It has now been found that this novel process can be applied with excellent results to the preparation of monoalkyl ethers of 3,4 di-parahydroxyphenyl hexane (hexestrol), which exhibit an improved estrogenic quality, characterized by the production of estrus of increased duration, when administered in doses larger than the minimum physiological dose.

The present invention also includes as features of novelty the monoalkyl ethers of hexestrol, as prepared by the novel method of making such ethers and of medicinal products containing them.

The subject matter of this application was originally presented in the joint application of applicant and Bernard J. Ludwig, Serial No. 375,446, filed January 22, 1941, and cancelled therefrom in response to a requirement for division.

Hexestrol is a perfectly symmetrical compound which may be represented by the following formula:

The new alkylated ethers forming the basis of the present disclosure can be represented by the type formula:

wherein R is an alkyl or aralkyl group of any 50 is further recrystallized from petroleum ether

suitable structural configuration. This substituent group may be a primary or secondary, a cyclic, or a branched chain, and may include one or more unsaturated linkages.

These monoalkyl ethers of hexestrol can be produced in the following manner, and this method, disclosed in the parent application, above identified, has been found to give improved results generally in the monoalkylation of poly-phenols, as will appear more in detail hereinafter. Considering the method as applied to monoalkyl ethers of hexestrol, a suitable process may be carried out as follows:

Hexestrol, i. e., 3,4 di-parahydroxyphenyl hexane, together with an alkyl halide, and alcoholic alkali, are mixed, in such proportions that the alkali is present in an amount about 5% less than one equivalent, calculated upon the hexestrol, and the alkyl halide is present in excess, this excess being large when using low boiling alkyl halides, such as methyl iodide, where approximately two equivalents constitute a suitable amount, whereas with higher boiling halides a 10% excess is sufficient. The three compounds in the recited admixture are held at an elevated temperature of the order of 37.5 to 80° C., depending upon the boiling point of the alkyl halide used, for a period of twelve to forty-eight hours, depending upon the temperature used. Under the conditions of the reaction monoalkylation of the hexestrol present takes place during this time to a much larger degree than dialkylation. Upon completion of the reaction, as determined by the disappearance of free alkali, the mixture containing the reaction products is precipitated by the addition of water and sufficient dilute acid to render the mixture acid in reaction, filtered, and the residue thoroughly extracted with aqueous alkali to remove any unreacted hexestrol. The washed residue is then thoroughly extracted with $\frac{1}{2}$ normal alkali dissolved in 40% to 45% alcohol, in which solvent mixture only the monoalkylated hexestrol is soluble, and a small amount of dialkylated hexestrol is left behind as a by-product. The dissolved monoalkyl ether of hexestrol is then precipitated with acid, filtered off and then recrystallized from aqueous acetone or aqueous alcohol wherein any traces of residual dialkylated hexestrol are insoluble. The monoalkyl product

until the desired purity has been reached as indicated by a constant melting point and concordant analyses.

The compositions used in making typical products of the invention, together with the conditions of reaction, yields, and properties of the end products are given in the following table:

Alkyl ether	Methyl	n-Butyl	n-Amyl
Hexestrol	2.0 grams	1.3 grams	1.3 grams.
Potassium hydroxide	.95 equivalent	.95 equivalent	.95 equivalent.
Water	18 cc.	6 cc.	6 cc.
Alcohol	13 cc. (abs.)	7 cc. (abs.)	7 cc. (abs.).
Alkyl halide in excess	MeI	n-BuBr	n-AmBr
Temperature	37.5°	65-80°	65-80°
Time	36 hours	12 hours	12 hours.
Yield di(crude)	5-15%	5-15%	5-15%
Yield mono (crude)	60-80%	60-80%	60-80%
M. P. mono-ether	118.5°	105.5°	100.5°
M. P. di-ether	144°	107.5°	88.5°
Oestrogenic activity ¹	Less than 8 gamma	50 gamma	125 gamma.

¹ Weight required to produce estrus in ovariectomized rats.

The methyl, butyl and amyl groups in the ethers shown in the above table are examples of alkyls containing 1 to 5 carbon atoms.

To recapitulate, the mono-ethers of hexestrol and other poly-phenols exhibit improved physiological qualities over the parent compounds. Where such parent compounds produce an estrus of passing duration of the order of 2 or 3 days, it is to be noted that the mono-ethers of hexestrol are characterized by the capacity to produce estrus of increased duration. The duration of the estrus may be increased at will by increased doses, and without undue physiological effects, or undesirable manifestations.

The monoalkyl ethers of the present invention may be identified and tested chemically and physiologically in any well known manner, details of such tests being given in the Reid application 5 above referred to.

It will be understood that the details given are for the purpose of illustration, not description,

and any variations within the spirit of the invention are intended to be included in the scope of the appended claims.

What is claimed is:

1. 3 - paramethoxyphenyl - 4 - parahydroxy-phenyl.

2. A chemical compound of the type formula:

in which R is an alkyl radical containing 1 to 5 carbon atoms.

CERTIFICATE OF CORRECTION.

Patent No. 2,385,472.

September 25, 1945.

FRANZ C. SCHMELKES.

It is hereby certified that error appears in the printed specification of the above numbered patent requiring correction as follows: Page 2, first column, line 25, for "mon-ethers" read --mono-ethers--; and second column, line 27, claim 1, after "phenyl" insert --hexane--; and that the said Letters Patent should be read with this correction therein that the same may conform to the record of the case in the Patent Office.

Signed and sealed this 15th day of January, A. D. 1946.
